US00D875692S

(12) **United States Design Patent** (10) **Patent No.:** **US D875,692 S**
(45) **Date of Patent:** **** Feb. 18, 2020**

(54) **LED CONTROLLER**

(71) Applicant: **Jianjie Shi**, Puyang He'nan (CN)

(72) Inventor: **Jianjie Shi**, Puyang He'nan (CN)

(**) Term: **15 Years**

(21) Appl. No.: **29/708,825**

(22) Filed: **Oct. 9, 2019**

(51) **LOC (12) Cl.** **14-03**

(52) **U.S. Cl.**

USPC **D13/168**

(57) **CLAIM**

An ornamental design for a LED controller, as shown in the drawings and described herein.

DESCRIPTION

FIG. 1 is a perspective view of a LED controller showing the claimed design;

FIG. 2 is a top plan view thereof;

FIG. 3 is a rear elevational view thereof;

FIG. 4 is a bottom plan view thereof;

FIG. 5 is a right side view thereof;

(Continued)

FIG. 6 is a front elevational view thereof; and,
FIG. 7 is a left side view thereof.
